UNITED STATES PATENT OFFICE.

HENRY WALKER, PERCY SIDNEY WALKER, AND JOHN HAMER, OF CHARLTON, ENGLAND.

HORSESHOE.

SPECIFICATION forming part of Letters Patent No. 735,322, dated August 4, 1903.

Application filed October 20, 1902. Serial No. 128,072. (No model.)

To all whom it may concern:

Be it known that we, HENRY WALKER, PERCY SIDNEY WALKER, and JOHN HAMER, subjects of the King of Great Britain, residing at Charlton, in the county of Kent, England, have invented certain new and useful Improvements in Horseshoes, of which the following is a specification.

Our invention relates to improvements in and connected with horseshoes, and has for its object cold shoeing and the provision of means for preventing the destroying of the animal's hoof through the practice of too often removing the shoe therefrom.

15 A further object of our invention is to provide means for securely fixing in position on the horseshoe special wearing-surfaces—such as detachable protectors, calks, roughing attachments, or the like—which may be easily 20 and quickly removed and fixed in position again as required without having to remove the horseshoe from the animal's hoof.

In carrying our invention into practice we provide a horseshoe constructed of three or 25 more pieces, which pieces are hinged or pivoted together. In conjunction with this sectional shoe we provide removable protectors or calks and roughing attachments capable of being securely fastened by slotted set- 30 screws, which are locked by split pins.

In order that this our said invention may be the more readily understood and carried into practical effect, reference is hereby made to the accompanying sheet of illustrative 35 drawings, wherein—

Figure 1 is a plan view of our improved shoe shown independently. Fig. 2 is a side elevational view thereof. Fig. 3 is a front elevational view. Fig. 4 is a front elevational view 40 of the form of our improved protector or calk adapted for attachment to the toe of the shoe. Fig. 5 is a side elevational view of our improved protector or calk adapted for attachment to the heel of the shoe. Fig. 6 is a view 45 of the screw-stud we employ for securing the protectors or calks in position on the shoe. Fig. 7 is a view of a modified form of securing-stud. Fig. 8 is a view of a split pin which is used in conjunction with the securing-stud 50 for holding the protectors or calks securely in position. Fig. 9 is a plan view of the snow-

calk or roughing attachment we employ in frosty weather. Fig. 10 is a side elevational view thereof. Fig. 11 is a plan view of our improved horseshoe fitted with our improved 55 protectors or calks ready for use. Fig. 12 is a side view thereof, while Fig. 13 is a section upon line A B of Fig. 11.

Referring to the drawings, in which like numerals of reference indicate corresponding 60 parts wherever occurring throughout all the figures, the numeral 1 designates the toe portion of the horseshoe, to which the heel portion 2 is hinged or pivoted, as at 3, an intermediate washer 4 being arranged between the 65 two sections 1 and 2. This intermediate washer 4 and also the pivoted ends of the sections 1 and 2 are preferably tinned or plated to prevent the hinged joint becoming locked by rust. A mitered, dovetailed, or other groove 70 5 is cut in the toe portion 1 of the horseshoe, and similar grooves 6 are cut in the heel portions 2 thereof. These grooves are arranged to receive removable protecting pieces or calks 7, which protecting pieces or calks are provided 75 with miters or dovetails 8, such miters or dovetails corresponding with the grooves 6, cut in the horseshoe proper. These calks 7 are secured to the horseshoe proper by means of the special studs 9, which studs are screw- 80 threaded for the greater portion of their length and terminate at their inner ends in a pin of reduced diameter, 10. The said studs 9 are provided with longitudinal slots 11 and are arranged to be screwed into tapped open- 85 ings in the calks 7, the reduced inner end taking into a hole or recess 12 in the horseshoe proper. Split pins 13 are provided, which split pins pass through holes 14 in the calks 7 and through the slots 11 in the studs 90 9, thus preventing the studs from working loose through vibration or from other causes.

In snowy or frosty weather the ordinary calks 7 may be removed and the roughing attachment 15 (illustrated by Figs. 9 and 10) 95 utilized in place thereof.

It will be understood that we may construct our horseshoe in any number of convenient hinged sections and of any suitable material. We may also, if desirable, strengthen 100 those parts of the shoe proper which carry the calks and reduce the thickness of the

other portions of the shoe proper correspondingly. It is also obvious that our improved calks may be applied to horseshoes constructed in one piece.

5 In the event of it being desirable to employ calks of a material such as india-rubber we employ the stud 16 (illustrated by Fig. 7) for securing such calk to the shoe proper. This stud 16 is of similar construction to the stud 9, except that the main portion of such stud is left plain and the inner reduced end 17 is screw-threaded and arranged to engage with a tapped opening in the shoe proper. It will be understood that the shoe proper is attached 10 to the hoof of the horse by means of nails in the ordinary manner, except that by means of its sectional construction the shoe can be fitted to the hoof cold.

What we claim as our invention, and desire 20 to secure by Letters Patent of the United States, is—

In horses' shoes the combination with an inner shoe and removable wearing-surfaces arranged to be carried by said inner shoe; of

the means for enabling the wearing-surfaces 25 to be securely held upon the said inner shoe and readily removable therefrom, said means comprising the provision of a suitable dovetailed groove in the surface of the inner shoe and a corresponding dovetail on the inner 30 face of the removable wearing-surface, in combination with a longitudinally-slotted stud screw-threaded for the greater portion of its length and terminating in a pin of reduced diameter on its inner end, said stud 35 operating in conjunction with a tapped opening in the removable wearing-surface and a hole or recess in the inner shoe and being held securely in position by means of a split pin passing through a transverse hole in the removable wearing-surface and the slot of said stud substantially as specified.

HENRY WALKER.
